(57) CLAIM

The ornamental design for vest, as shown and described.

DESCRIPTION

The file of this patent contains at least one drawing executed in color. Copies of this patent with color drawings will be provided by the Office upon request and payment of the necessary fee.

FIG. 1 is a right perspective view of a vest;

FIG. 2 is a front view of the vest in FIG. 1;

FIG. 3 is a rear view of the vest in FIG. 1;

FIG. 4 is a right-side view of the vest in FIG. 1;

FIG. 5 is a left-side view of the vest in FIG. 1;

FIG. 6 is a top view of the vest in FIG. 1;

FIG. 7 is a bottom view of the vest in FIG. 1; and,

FIG. 8 is a front open view of the vest in FIG. 1.

The broken lines in the drawings, including the reflective strips outlined in broken lines in the drawings, are for illustrative purposes only and do not form part of the claimed design.
